UNITED STATES PATENT OFFICE.

BENNETT F. CLARK, OF GENEVA, NEW YORK, ASSIGNOR TO THE STANDARD OPTICAL COMPANY, OF GENEVA, NEW YORK, A CORPORATION OF NEW YORK.

LENS-GRINDING MACHINE.

No. 927,949.

Specification of Letters Patent. Patented July 13, 1909.

Application filed June 3, 1908. Serial No. 436,449.

To all whom it may concern:

Be it known that I, BENNETT F. CLARK, of Geneva, in the county of Ontario, in the State of New York, have invented new and useful Improvements in Lens-Grinding Machines, of which the following, taken in connection with the accompanying drawings, is a full, clear, and exact description.

This invention relates to certain improvements in lens grinding machines in which the lens is rotated with its edge in contact with the face of a suitable grindstone for the purpose of giving form and size to the lens, the form being regulated by a master pattern having its axis coaxial with the mechanical axis of the lens and riding against a suitable abutment for determining the size and form of the lens.

The main object of my present invention is to combine the grinding mechanism, lens holder and truing device together with the various adjusting devices and actuating mechanisms in a single compact machine and with as few parts as may be consistent with the various functions which the machine as a whole is adapted to perform.

One of the specific objects of my present invention is to provide means for simultaneously stopping the action of the machine when the lens holder with the lens therein is moved away from the grindstone and also for throwing the mechanism into action when the lens holder is forced to its operative position for grinding the lenses.

Another specific object is to provide a simple and practical means whereby the degree of pressure of the lens clamps upon the lens may be varied at will during the operation of the machine.

A further object is to provide means for varying the degree of pressure of the lens against the grindstone, and a still further object is to provide a simple, and practical adjusting means for the contact plate for the lens form or pattern and for varying the sizes of the lenses according to graduations with which the adjusting device is provided.

Another object is to provide simple means for automatically reciprocating the grindstone axially so as to bring all parts of its grinding face into contact with the lenses during the grinding operation thereby avoiding undue wear in any one particular place.

Another object is to permanently associate with the grinding mechanism a suitable tru-

ing device for keeping the face of the grindstone exactly concentric and parallel with the axis.

Other objects and uses will be brought out in the following description.

In the drawings—Figures 1 and 2 are respectively a top plan and side elevation of a lens grinding machine embodying the various features of my invention. Figs. 3, 4, 5, 6, 7, 8 and 9 are sectional views taken respectively on lines 3—3, 4—4, 5—5, 6—6, 7—7, 8—8 and 9—9, Fig. 1, Figs. 5, 6, 7, 8 and 9 being enlarged.

In carrying out the objects stated I provide a substantially rectangular supporting base or frame —1— which is provided with suitable feet and adapted to rest upon a bench, table or other available support and upon which is mounted the several coacting mechanisms of the complete machine as will be hereinafter described. This frame is preferably made of cast iron or other suitable metal and is provided with an integral substantially semi-circular hopper —2— centrally therein and open at the top for receiving the lower half of a grindstone —3—, the transverse interior width of the hopper or grindstone receptacle being somewhat greater than the corresponding width of the grindstone to permit axial movement of the latter in either direction. This grindstone is provided with a comparatively large central circular opening —4— in which is fitted a circular disk —5—, the grindstone being secured to the periphery of the disk —5— by an interposed bond —6— of melted sulfur or other adhesive or cementitious material so that the disk and securing means of the grindstone lie wholly within the plane of said grindstone thereby obviating the usual clamping disks and lock nut at opposite sides of the stone.

The disk —5— is preferably formed of metal and is centrally mounted upon a revolving shaft —7— which in this instance extends some distance beyond the faces of the grindstone and is journaled at its opposite ends in suitable bearings —8—. These bearings —8— are adjustable forwardly and rearwardly along and upon the grindstone receptacle or hopper —2— as best seen in Figs. 4 and 7 and for this purpose the upper edges of the hopper —2— are formed with laterally projecting flanges having lengthwise slots —9— for receiving the lower ends

of clamping bolts —10— which are passed through apertures in the front and rear portions of the bearings —8— and engage threaded plates —11— on the under sides of said flanges whereby the bearings and shaft —7— together with the disk —5— and grindstone —3— may be held in their adjusted position, the object of this adjustment being to permit the grindstone to be shifted 10 toward the lens holder as it is worn away by abrasion.

One end of the grindstone shaft —7— is provided with a driving pulley —12— adapted to be connected to any available 15 source of power by a belt, not shown. The opposite end of said shaft is provided with a drive worm —13— meshing with an underlying worm gear —14— which is loosely mounted upon a shaft —15— to permit the 20 driving shaft —7— and parts rigidly mounted thereon together with the worm gear —14— to be continuously rotated independently of the rotation of the lens holder and its driving mechanism, presently described.

The shaft —15— is journaled in suitable bearings —16— and —17— as best seen in Figs. 2 and 5, one of which as the bearing —16— is preferably integral with the main 30 supporting frame or bed —1— while the bearing —17— forms a part of a bracket —18— which is secured by one of the clamping screws —10— to the adjacent bearings —8— and is, therefore, movable with the 35 grindstone when the latter is adjusted toward or from the lens holder in the manner previously referred to and is also adapted to slide along the shaft —15—, the latter being held from lengthwise movement by a collar 40 —19— and a worm —20— located at opposite ends of and in close proximity to the bearing —16— as best seen in Fig. 5. This shaft —15— is adapted to be thrown into and out of operative connection with the 45 worm gear —14— by means of a sliding clutch element —21— which is feathered or splined upon the rear end of the shaft —15— and is movable into and out of interlocking engagement with the adjacent face of a worm 50 gear —22—, the latter forming a part of the driving mechanism for reciprocating the grindstone axially while the worm —20— at the opposite end of the shaft forms a part of the mechanism for rotating the lens holder 55 and pattern coaxial therewith, both of which mechanisms will be presently described. The worm —22— meshes with a worm gear —23— which is loosely mounted upon a supporting pin or stud —24— and is provided 60 at its outer end with a hub —25— having a cam groove —26— therein for receiving a stud or roller —27—. This stud or roller is mounted upon the upper end of a laterally swinging arm or bracket —28— having its 65 upper end slotted and engaged with the ad-

jacent end of the grindstone shaft —7— between a pair of shoulders —29— while its lower end is fulcrumed or pivoted upon a suitable supporting pin —30— as best seen in Fig. 4.

The worm —22—, gear —23— and cam collar —25— together with the roller stud —27— and laterally swinging arm —28— constitutes mechanism for shifting the grindstone and its supporting shaft axially or 75 across the edge of the lens and when the clutch —21— is thrown out of operative connection with the worm —22— and worm gear —14— by sliding it rearwardly lengthwise of the shaft, the grindstone together with its axially shifting mechanism may be rotated continuously independently of the lens holder during which time the grindstone may be trued by a suitable abrasive tool —31— which is adjustably clamped in a 80 sliding support —32—, the latter being adjustable radially in a suitable supporting frame —33— on the rear end of the hopper —2—, said sliding support —32— and abrasive cutter —31— thereon being adjustable 85 radially of the hand screw —34— as best seen in Fig. 9 although the abrasive body —31— has an independent adjustment and is held in place by a clamp plate —35— and suitable clamping screws —36— as best seen 90 in Fig. 9.

The supporting frame —33— is preferably secured to the upper face of the rear end of the hopper —2— by screws —38— also seen in Fig. 9 and it is, therefore, evident that this 100 entire truing device forms a permanent part of the complete machine and is always ready for use and may be brought into action at any time either during the grinding of the lens or when the lens holder is thrown out of 105 action.

The clutch element —21— is thrown into and out of operative connection with the worm gear —14— or rather with the worm —22— thereon through the medium of a 110 hand lever —37—, link —39— and intermediate upright lever —40—, the latter lever being fulcrumed at —41— intermediate its ends and has its lower end provided with a stud —42— which rides in an annular groove 115 in the clutch member —21— while the upper end of said lever —40— is connected with a loss motion to a head —43— on the rear end of the link —39—. The hand lever —37— is fulcrumed at its lower end at —44— to the upper side of the bearing —16— and is connected intermediate its ends to the adjacent end of the link —39— while its upper end is provided with a suitable hand piece by which it may be manipulated backward and forward 120 to rock the lever —40— and thereby shift the clutch element —21— to connect and disconnect the shaft —15— to and from the loose worm gear —14— thereon. This 125 clutch element and its operating mechanism 130

which I have just described constitutes the means for controlling the rotary action of the lens holder and its driving mechanism which I will now proceed to describe.

5 The worm —20— meshes with a superposed worm gear idler —50— which is rigidly secured to one end of a horizontal shaft —51— and meshes with a superposed gear —52—, the opposite end of said shaft being 10 also provided with a pinion —53— rigid thereon and meshing with a superposed gear —54— which is coaxial with the gear —52—. The opposite ends of the shaft —51— are journaled in suitable bearings —55— rising 15 from the top of opposite ends of the supporting bed or frame —1—, said shaft —51— revolving in the bearings and forming a bearing for a rocking frame —56— as best seen in Fig. 6 and upon which the lens holder is 20 mounted in a manner which I will now describe.

The swinging frame —56— is provided with opposite upright bearings —58— and —59—, one of which as the left end bearing —58— receives and supports a revoluble spindle —60— which extends entirely through the bearing —58— and receives at its outer end the gear —54— while the inner end is provided with an enlarged head —61—; the hub of the gear —54— and head —61— engaging the opposite end faces of the bearing —58— to hold the spindle against endwise movement. The head —61— is provided with a central inwardly projecting stud —62— and eccentric pin —63— which enter corresponding apertures in a pattern or lens forming plate 64— for locking said plate to the head —61— to rotate with the spindle —60—. This machine is adapted to grind, form and size one or a plurality of lenses at once and in order that these lenses may be expeditiously and correctly placed in the lens holder with their optical axes in registration with each other 45 and with that of the pattern or former, I provide the spindle 60— with an auxiliary removable head —65— which is formed with central and eccentric apertures registering with and receiving the central stud —62— and pin —63— whereby said head —65— is locked to rotate with the spindle —60— but is removable endwise from or with the pattern —64— when necessary, as for instance when properly positioning the lens relatively 50 to the pattern or former —64—. This auxiliary head —65— is particularly useful in connection with a lens adjusting tool, not shown, and forming the subject matter of my pending application No. 436,448, filed 55 June 3, 1908 not necessary to herein illustrate or describe, it being sufficient to say that the auxiliary head —65— is provided with a flange similar in general outline to the contour of the pattern 64— and is provided 60 with a yielding engaging face —66— of rubber

or other equivalent material which may be adhesively secured to the adjacent face of the auxiliary head —65—.

Coacting with the clamping head —65— to hold the lens or lenses in operative position for grinding is a second coaxial clamping head —67— having a yielding or flexible friction face —68— of rubber or other suitable material, said clamping head —67— being loosely mounted upon the adjacent end 70 of a rotary spindle —69— which is feathered or splined to and within a rotary sleeve —70— as best seen in Fig. 6. This sleeve —70— is journaled directly in the bearing —59— and surrounds the intermediate portion 75 of the spindle —69—, the inner end of said sleeve being provided with an annular flange —71— engaging the adjacent end of the bearing —59— to prevent endwise movement of said sleeve in one direction while the gear —52— is secured to the opposite end of the sleeve and engages the adjacent end of the bearing —59— to hold said sleeve against endwise movement in the opposite direction, 80 said gear —52— being locked to the sleeve by a screw pin —72— which also enters a key way —73— in the spindle —69— to allow the latter to be adjusted endwise relatively to the clamping head —65— to hold or release the lenses which may be clamped 85 between said heads. The end of the spindle —69— adjacent to the clamping head —67— is enlarged forming an annular shoulder —74— upon which the adjacent end of the sleeve —70— is closely fitted with a sliding 90 fit while the opposite end of said sleeve is similarly fitted upon the reduced portion of the spindle leaving the intermediate portion of the sleeve of somewhat greater diameter than the inclosed portion of the spindle for 95 the reception of a coil spring —75— having its opposite ends interposed between the annular shoulder —74— and opposite end of the sleeve for the purpose of forcing the spindle —69— and its clamping head —67— endwise toward the clamping head —65— thereby 100 clamping the lens or lenses between the heads —67— and —65— under a yielding pressure. The tension of this spring —75— may be varied at will at any time while the 105 machine is at rest or during the operation of grinding by means of a hand nut —76— which is coaxial with the spindle —69— and is screwed upon a fixed threaded hub —78— as best seen in Fig. 6, said spindle being extended 110 through the hub —78— and into the hand nut —76— and is provided at its outer end with an annular shoulder —79— which engages an internal annular shoulder —80— on the hand nut —76—, sufficient space being 115 left between the annular shoulder —79— and adjacent end of the hub —78— to allow a limited endwise movement of the spindle in the hub and also in the sleeve —70—. The annular shoulder —79— preferably con- 120

sists of a washer which is detachably secured to the adjacent end of the shaft or spindle —69— by means of a screw —82— which when removed permits the removal of the 5 washer —79— and also enables the hand nut —76— to be detached or unscrewed from the hub —73—.

It is now obvious that when it is desired to place a lens or lenses between the clamping 10 heads it is simply necessary to press the head —67— and its supporting spindle —69— back or against the action of the spring —75— by hand and sufficient to permit the lens or lenses to be properly placed between 15 the clamping heads, and when said lens or lenses are so placed the clamping head —67— and spindle —69— may be released to allow the spring —75— to force the spindle and its clamping head —67— toward the opposite 20 clamping head —65— thereby clamping the lenses in place under a yielding pressure.

It will be evident from the foregoing description that the spindles —60— and —69— are separately but positively driven 25 by the pinions —50— and —53— meshing with their respective gears —52— and —54— which latter are of the same pitch diameter and therefore the spindles are driven at the same rate of speed.

30 The upper portion of the swinging frame —56— upon which the spindles —60— and —69— are mounted is movable toward and from the front face of the grindstone —3— and is drawn rearwardly by means of a coil 35 spring —86— having one end attached at —87— to one of the bearings as the bearing —58— while the opposite end is attached to the upper end of an upright lever —89— which is fulcrumed at —90— intermediate 40 its ends and having its lower end connected by a cord or cable —91— to a rotary drum —92—. This drum is secured to and forms a part of a rotary adjusting spindle —93— which is journaled with a comparatively 45 tight friction fit in the front part of the frame —1— preferably in the lower side of the bearing —55— and is provided with a hand piece —94— by which it may be rotated in one direction or the other to wind or 50 unwind the cord or cable —91— thereby operating the lever —89— to vary the tension of the spring —86— and permitting the edges of the lens to be forced against the grinding face of the grindstone with more or 55 less pressure as may be desired. The means for rocking the frame —56— in the opposite direction against the action of the spring —86— to force the lens holder away from the 60 grindstone and thereby throw the lenses out of engagement with the grindstone consists of the lever —37— which is located just at the rear of and engages the bearing —59— so that when the lever —37— is drawn forwardly by hand it will engage the rear face 65 of the bearing —59— and thereby rock the

upper portion of the frame —56— forwardly against the action of the spring —86—, said frame being locked in operative position by a detent or shoulder —98— which interlocks with a corresponding shoulder —99— 70 on the rear side of the bearing —59— as best seen in Fig. 5. As previously stated, when the lever —37— is rocked forwardly in the manner just described to throw the lens holder and its supporting frame —56— to its 75 inoperative position, the driving mechanism which rotates the lens holder is simultaneously thrown out of action through the medium of the link —39— and its connection with the lever —40— and clutch element 80 —21— and in order that the clutch may be connected and disconnected to the driving element —14— at the limit of movement of the lens holder and its supporting frame toward and from the grindstone, the head 85 —43— is provided with shoulders —43'— which are spaced some distance apart at opposite sides of the adjacent end of the lever —40— with which they are adapted to engage as the link —39— is reciprocated back- 90 wardly and forwardly by the action of the lever —37—. In other words, when the lever is thrown forwardly to force the lens holder away from the grindstone the rear shoulder —43'— engages and operates the lever 95 —40— to throw the clutch section —21— out of interlocking connection with the driving element —22— and when said lever is thrown rearwardly to allow the spring to draw the lens holder toward the grindstone, 100 the forward shoulder —43'— is similarly engaged with and operates the lever —40— to throw the clutch section —21— into operative engagement with the driving element —22—, it being understood that during the 105 retraction of the lens holder and its supporting frame by the spring —86—, the lever —43— may be gradually released to allow the lenses to be drawn against the face of the 110 grindstone under light pressure thereby avoiding any liability of cracking or breaking the lenses by undue force of contact. The distance between the shoulders —43'— on the head —43— is considerably greater than the width of the shoulders —98— and —99— on the lever —37— and bearing —59— respectively which permits the lens holder supporting frame to be released and 115 swung rearwardly to bring the lenses into engagement with the grindstone without re-engaging the clutch section —21— with the driving element —22—. This operation is very often desirable to enable certain parts of the lenses requiring more grinding than other parts to be brought into engagement with the grindstone, and for this purpose the front end of the shaft —15— is extended forwardly and provided with a suitable hand wheel —100— by which the shaft and connection between it and the driving 120 125 130

spindle may be rotated by hand independently of the continuously rotating driving element —14— or —22— thus permitting certain portions of the lenses to be ground irrespective of other portions.

In order that the lenses may be ground to a certain size and form, the form corresponding to that of the master pattern —64—, I provide an adjustable bearing or stop —101— against which the periphery of the master pattern —64— may ride as the lens is ground to the desired size. This back rest or stop —101— as best seen in Fig. 7 is removably secured to the upper 10 end of an upright support —102— and is located in a plane coincident with a line drawn between the axis of the grindstone shaft and lens holder, its contact face being substantially concentric with the axis of, 15 and of a radius corresponding nearly to that of the grindstone and both its front and rear end are preferably of the same form so that it may be reversed or its ends interchanged for contact with the master pattern. The 20 support —102— for the back rest —101— is adjustable forwardly and rearwardly to vary the position of the contact face of said back rest thereby affording means for grinding lenses to different sizes, said support 25 being held from lateral displacement by and is guided upon a suitable fixed guide —103— on the main supporting frame or bed —1— while its lower end is mounted upon a rotary and axially adjustable spindle 30 —95— as best seen in Fig. 7. This spindle is mounted in a suitable guide or bearing —104— and is provided with an annular shoulder —105— forming an abutment for one end of a coil spring —106— which surrounds the intermediate portion of the spindle within the bearing —104—, the opposite end of said spring abutting against the adjacent end of a sleeve —107— which is fitted 35 in the outer end of the bearing —104—. 40 This spindle is provided with a threaded outer end —108— which is engaged by a hand rotated nut —109—, the latter being provided with a series of graduations corresponding to different sizes of lenses and 45 movable into registration with a fixed graduation on the adjacent portion of the bearing —104—, the rotation of the nut —109— serving to move the support —102— and back rest —103— forwardly or rearwardly 50 a predetermined distance according to the direction of rotation of the nut —109—, the amount of adjustment and size of the lens being determined by the graduation on the nut which may be brought into registration 55 with the fixed graduation —110—. As a further means of adjustment for the back rest —101—, the rear end of the spindle —95— is threaded and screwed into a threaded aperture in the lower end of the support —102— 60 and the front end of said spindle is extended 65

through the nut —109— and provided with a suitable hand piece —112— which permits the back piece to be adjusted to conform to the graduations on the adjusting nut —109—, the spring —106— serving to 70 force the spindle rearwardly, thereby holding the nut —109— in frictional contact with the adjacent end of the bearing —104—.

The operation of my invention is as follows, assuming that the grindstone is in action or being rotated by any available source of power, not shown, but connected to the pulley, the lens holder is drawn backwardly against the action of the spring —86— by the lever —37— to the position shown in Fig. 2 in which the clutch section —21— is thrown out of action and the lens supports are at rest whereupon the lens or lenses are placed between and closed by the lens holder in the manner previously described and the back 80 rest —101— is then adjusted to give the finished lens the desired size as indicated by the graduations upon the nut —109—. The lever —37— is gradually thrown backwardly by hand allowing the spring —86— to draw 90 the lens holder and its supporting frame rearwardly to bring the edge of the lenses into engagement with the periphery of the grindstone. When the edges of the lenses are thus brought into contact with the grindstone, the lever —37— is further shifted rearwardly to bring the forward shoulder —43'— into engagement with the upper end of the lever —40— thereby rocking the lever and forcing the clutch section —21— into operative engagement with the continuously rotating driving element —22— whereupon rotary motion will be instantly transmitted to the lens holders and lenses through the medium of the shaft —15— and gears —20—, —50— 100 and —52— and also the gears —53— and —54— to the spindles —60— and —69— thereby rotating the lenses in the direction indicated by the arrow —M—, Fig. 2 while the grindstone is rotated in the direction indicated by arrow —N—. The operation of grinding now takes place and continues until limited by the engagement of all points in the periphery of the master pattern —64— with the back rest or limiting stop —101—. 110

If for any reason certain portions of the periphery of the lenses need more grinding than others the lever —37— may be rocked forwardly sufficient to throw the clutch —21— out of action thereby stopping the rotation of the lens holder and permitting such rotation to be effected through the medium of the hand piece —100— as previously described.

What I claim is:

1. In a lens grinding machine, a rotary grindstone, and a rotary lens holder comprising coaxial rotary spindles, one of said spindles having projecting pins, a lens pattern having apertures receiving said pins and re- 125 130

movable therefrom, and a lens clamping head also provided with apertures receiving said pins and removable therefrom independently of the lens pattern.

- 5 2. In a lens grinding machine of the class described, a rotary axially movable grindstone, a rotary lens holder and support therefor movable toward and from the face of the grindstone, an intermediate shaft forming part of the mechanism for transmitting motion from the grindstone shaft to the lens holder, means including a clutch for transmitting motion from the grindstone shaft to the intermediate shaft, additional means actuated by the grindstone shaft for moving said shaft axially when the clutch is in action and out of action, further means for transmitting motion from the intermediate shaft to the lens holder, and means for rotating the intermediate shaft to rotate the lens holder when the clutch is out of action.

- 20 3. In a machine of the class described, a rotary grindstone and supporting shaft therefor, a rotary lens holder, an intermediate shaft forming a part of a power transmitting mechanism between the grindstone shaft and lens holder, a rotary element loose on the intermediate shaft, means on the grindstone shaft for rotating said rotary element, a clutch for connecting and disconnecting said rotary element to and from the intermediate shaft, means for operating said clutch at will, and means for transmitting motion from the intermediate shaft to the lens holder.

- 25 4. In a lens grinding machine of the character described, a rotary grindstone and supporting shaft therefor, a rotary lens holder, an intermediate shaft forming part of an operative connection between the grindstone shaft and lens holder, means movable independently of the intermediate shaft for reciprocating the grindstone axially, means for connecting and disconnecting said last named means to and from the intermediate shaft, and additional means for transmitting rotary motion from the intermediate shaft to the lens holder.

- 30 5. In a lens grinding machine of the class described, a rotary grindstone and a supporting shaft therefor, a rotary lens holder, means actuated by the grindstone shaft for reciprocating the grindstone axially, additional means including a clutch for transmitting rotary motion from the grindstone reciprocating means to the lens holder, means operated at will for actuating the clutch, and means for rotating the intermediate shaft and lens holder connected thereto independently of the rotation of the grindstone when the clutch is shifted to its inoperative position.

- 35 6. In a lens grinding machine of the class described, a rotary and axially movable

grindstone and supporting shaft therefor, an upright lever operatively connected to the end of the shaft, and means actuated by the rotation of the grindstone shaft for operating said lever.

7. In a lens grinding machine of the class described, a rotary grindstone and supporting shaft therefor, a rotary lens holder, an intermediate shaft forming part of a power transmitting mechanism between the grindstone shaft and lens holder, means for making and breaking connection between the grindstone shaft and said intermediate shaft, and additional means movable independently of the intermediate shaft and actuated by the grindstone shaft for reciprocating the grindstone axially, and further means for transmitting motion from the intermediate shaft to the lens holder.

8. In a lens grinding machine of the class described, a rotary and axially movable grindstone and supporting shaft therefor, a rotary lens holder, an intermediate shaft forming part of a mechanism for transmitting motion from the grindstone shaft to the lens holder, a worm on the grindstone shaft, a worm gear loose on the intermediate shaft and meshing with said worm, a second worm rigid with said worm gear, a second worm gear meshing with the second worm, a cam rotating with the second worm gear, an upright lever and engaged and reciprocated by said cam and connected to the grindstone shaft for reciprocating the latter axially, a clutch splined on the intermediate shaft and movable into and out of connection with the second worm, means operable at will for shifting the clutch, means for transmitting rotary motion from the intermediate shaft to the lens holder, said intermediate shaft being provided with a hand wheel by which it may be rotated to rotate the lens holder independently of the grindstone shaft when the clutch is thrown out of action.

9. In a lens grinding machine of the class described, a rotary grindstone and supporting shaft therefor, a rotary lens holder, a support for the lens holder movable to and from the face of the grindstone, a spring for forcing the lens holder support toward the grindstone, means including a clutch for transmitting motion from the grindstone shaft to the lens holder, a lever operable at will for forcing the lens holder support away from the grindstone, and additional means brought into action by the lever for shifting said clutch.

10. In a lens grinding machine of the class described, a rotary grindstone and supporting shaft therefor, a rotary lens holder, a support for the lens holder movable to and from the face of the grindstone, a spring for forcing the lens holder support toward the grindstone, means including a clutch for

transmitting motion from the grindstone shaft to the lens holder, a lever operable at will for forcing the lens holder support away from the grindstone, and additional means brought into action by the lever for shifting said clutch, and means on the lever for engaging the lens holder support and holding it in its inoperative position.

11. In a lens grinding machine of the class described, a rotary grindstone and supporting shaft therefor, a rotary lens holder and movable support therefor, means including a clutch for transmitting motion from the grindstone shaft to the lens holder, a lever operable at will to force the lens holder support away from the grindstone.

12. In a lens grinding machine of the class described, a grinding element, a rotary lens holder and supporting frame therefor movable toward and from the grinding element, a spring for drawing the supporting frame toward the grindstone, and a lever for engaging and forcing the lens holder supporting frame away from said element against the action of the spring.

13. In a lens grinding machine of the class described, a grinding element, a rotary lens holder and supporting frame therefor movable toward and from the grinding element, a spring for drawing the supporting frame toward the grindstone, and a lever for engaging and forcing the lens holder supporting frame away from said element against the action of the spring, and means for locking the lens holder supporting frame in its inoperative position.

14. In a lens grinding machine of the class described, a rotary grindstone, a rotary lens holder, means for transmitting rotary motion from the grindstone to the lens holder including a clutch, a support for the lens holder movable toward and from the grindstone, a spring for drawing said support toward the grindstone, a lever for moving the support away from the grindstone against the action of said spring, and connections between said lever and clutch for throwing the latter out of action when said support is moved away from the grindstone.

15. In a lens grinding machine of the class described, a rotary grindstone, a rotary lens holder, means for transmitting rotary motion from the grindstone to the lens holder including a clutch, a support for the lens holder movable toward and from the grindstone, a spring for drawing said support toward the grindstone, a lever for moving the support away from the grindstone against the action of said spring, and connections between said lever and clutch for throwing the latter out of action when said support is moved away from the grindstone, said lever having a limited movement independent of the clutch whereby the supporting frame for the lens holder may be moved to bring the

lens into engagement with the grindstone without throwing the clutch into action.

16. In a lens grinding machine of the class described, a rotary grindstone, a rotary lens holder, means for transmitting rotary motion from the grindstone to the lens holder including a clutch, a support for the lens holder movable toward and from the grindstone, a spring for drawing said support toward the grindstone, a lever for moving the support away from the grindstone against the action of said spring, and connections between said lever and clutch for throwing the latter out of action when said support is moved away from the grindstone, said lever having a limited movement independent of the clutch whereby the supporting frame for the lens holder may be moved to bring the lens into engagement with the grindstone without throwing the clutch into action, portions of the operating mechanism for the lens holder being operable independently of the grindstone when the clutch is out of action.

17. In a lens grinding machine, a grindstone, a rotary lens holder and swinging supporting frame therefor, a spring for drawing said frame toward the grindstone, a lever connected to the spring, a cable connected to the lever, and a rotary hand operated drum connected to the cable for winding and unwinding the same and thereby operating the lever to vary the tension of the spring.

18. In a lens grinding machine, a grindstone, a rotary lens holder, a lens pattern coaxial and rotating with the lens holder, a back rest for the pattern adjustable toward and from the axis of said pattern, a support for the back rest provided with a threaded aperture, and a rotary threaded spindle engaged in said aperture for adjusting the support and back piece.

19. In a lens grinding machine, a grindstone, a rotary lens holder, a lens pattern coaxial and rotating with the lens holder, a back rest for the pattern adjustable toward and from the axis of said pattern, a support for the back rest provided with a threaded aperture, and a rotary threaded spindle engaged in said aperture for adjusting the support and back piece, a fixed indicator, and a rotary graduated nut mounted on the threaded portion of the spindle and having its graduations movable into registration with said fixed indicator, said nut operating to move the spindle endwise as it is rotated for adjusting the back rest.

20. In a lens grinding machine, a grindstone, a rotary lens holder, a lens pattern coaxial and rotating with the lens holder, a back rest for the pattern adjustable toward and from the axis of said pattern, a support for the back rest provided with a threaded aperture, and a rotary threaded spindle engaged in said aperture for adjusting the support and back piece, a fixed indicator, and a

rotary graduated nut mounted on the threaded portion of the spindle and having its graduations movable into registration with said fixed indicator, said nut operating to move
5 the spindle endwise as it is rotated for adjusting the back rest, and a spring for moving the spindle in one direction.

In witness whereof I have hereunto set my hand this 26 day of February 1908.

BENNETT F. CLARK.

Witnesses:

SMITH A. HARRIMAN,
C. H. ANNAN.
